US00D698478S

(12) **United States Design Patent**
Randolph et al.

(10) **Patent No.:** **US D698,478 S**
(45) **Date of Patent:** **** Jan. 28, 2014**

(54) **LIGHTING FIXTURE**

- (71) Applicant: **Cree, Inc.**, Durham, NC (US)
(72) Inventors: **David N. Randolph**, Rougemont, NC (US); **John R. Rowlette, Jr.**, Raleigh, NC (US)
(73) Assignee: **Cree, Inc.**, Durham, NC (US)
(**) Term: **14 Years**
(21) Appl. No.: **29/456,927**
(22) Filed: **Jun. 5, 2013**

(57) **CLAIM**

The ornamental design for a lighting fixture, as shown and described.

DESCRIPTION

FIG. 1 is a first front isometric view of a lighting fixture according to the new design.

FIG. 2 is a top plan view of the lighting fixture of FIG. 1.

FIG. 3 is a second front isometric view of the lighting fixture of FIG. 1.

FIG. 4 is a first side elevation view of the lighting fixture of FIG. 1.

FIG. 5 is a second side elevation view of the lighting fixture of FIG. 1.

FIG. 6 is a third side elevation view of the lighting fixture of FIG. 1.

FIG. 7 is a first rear isometric view of the lighting fixture of FIG. 1.

FIG. 8 is a bottom plan view of the lighting fixture of FIG. 1; and,

FIG. 9 is a second rear isometric view of the lighting fixture of FIG. 1.

The broken lines shown on the drawings depict portions of the lighting fixture that form no part of the claimed design.

1 Claim, 3 Drawing Sheets
